TREATMENT OF UNDERGROUND FORMATIONS

Francis A. Boyle, Norwood, Pa., assignor to Sun Oil Company, Philadelphia, Pa., a corporation of New Jersey

No Drawing. Application May 2, 1956
Serial No. 582,066

6 Claims. (Cl. 252—8.55)

This invention relates to the treatment of petroleum-bearing underground formations for the purpose of facilitating the flow of hydrocarbons from the formation into a production well. More particularly, the invention is concerned with the use of aliphatic amines of relatively low molecular weight for treating formations to improve the flow of hydrocarbons therethrough while hindering the flow of water.

It has been proposed heretofore to treat oil bearing sands with various amine compounds of relatively high molecular weight to facilitate the production of oil from the formation. It is thought that beneficial effects are obtained by such treatment due to chemi-sorption of the amine on the sand surfaces, whereby the sand is rendered oleophilic or preferentially wettable by oil. This permits the oil to flow more freely through the formation while hindering the flow of water. In order to achieve this result, it has been considered heretofore that the amine employed should be of relatively high molecular weight so that the absorbed amine molecules will provide relatively large hydrocarbon groups that can function to alter the nature of the sand surfaces. Sand normally is hydrophilic, and it has been thought that the large hydrocarbon groups are necessary in order to have substantial effect in altering the character of the surfaces so as to make them oleophilic.

Amines which have been proposed heretofore for this purpose include such compounds as decylamine, hexadecylamine, dioctylamine, octadecylamine, lauryl dimethylamine and docosylamine. Such compounds are soluble in hydrocarbons and can be introduced into the formation in the form of a solution in a suitable hydrocarbon material, such as kerosene, diesel oil or crude oil. They are, however, essentially insoluble in water. This is disadvantageous in that the treating compound cannot readily reach all sand surfaces in the zone being treated due to the presence of protective water films which act as barriers. The presence of water in the formation thus hinders the amine treating agent in contacting the sand surfaces and becoming absorbed thereon. This tends to reduce the effectiveness of the treatment, thereby necessitating the use of larger amounts of the treating solution or requiring the well undergoing treatment to be shut in for longer periods before production can be resumed.

I have now found that effective treatment of petroleum-bearing formations to render the sands preferentially oil wettable can be accomplished by treating the formation with certain low molecular weight amines which are water soluble. According to the invention, straight chain aliphatic primary amines having 1-5 carbon atoms per molecule and having the amino group attached to a terminal carbon atom are employed to treat the formation and render its surfaces oleophilic. The amines specifically are methylamine, ethylamine, n-propylamine, n-butylamine and amylamine. All of these are highly soluble in water and are capable of dissolving in and diffusing through water films present in the formation, thus facilitating contact of the amine with surfaces and promoting

2

adsorption of the amine by the sand. Primary amines of low molecular weight which do not have the amino group attached to a terminal carbon atom such as isopropylamine, sec-butylamine, tert-butylamine, 2-amino pentane and 3-aminopentane, while being soluble in water are not effective for the present purpose and are not within the scope of the invention.

The treatment of an oil well according to the invention may be carried out by dissolving a minor amount of one

10 or more of the amines as specified above in a suitable hydrocarbon solvent, such as kerosene, gas oil, crude oil or the like, and introducing the solution through the borehole into the formation. Only a small proportion, e.g. less than 5% of the amine need be used in the solution for good results, although larger proportions may be employed if desired. Generally it is preferable that the amount of amine in the treating solution be within the range of 0.05-2.0% by weight, since it has been found that such small proportions can effectively and economically be employed to achieve the desired results. As the solution of treating agent flows from the borehole into the formation being treated, the amine contacts the sand surfaces, both by direct contact of the hydrocarbon solution of amine therewith and by dissolution of the low molecular weight amine in water films or channels and diffusion therethrough to the sand surfaces. Adsorption of the amine on the sand changes the character of the surfaces and renders them oleophilic. When the well is subsequently put back into operation, the oil can pass more readily through the treated zone whereas the flow of water from farther back in the formation toward the borehole is retarded. The treatment thus effects an increase in the ratio of oil to water produced from the well.

The invention also is useful in treating natural gas wells to improve the flow of hydrocarbons into the well. All formations bearing natural gas, like those bearing heavier hydrocarbons, contain interstitial or connate water which tends to retard the flow of hydrocarbons. The present invention may be utilized to increase the

40 permeability of the formation to gaseous hydrocarbons by introducing into the formation a low molecular weight primary amine which is gaseous under the temperature and pressure conditions prevailing in the well. For example, methylamine which has a normal boiling point of

45 -6.5° C. or ethylamine having a normal boiling point of 16.6° C. may be introduced in gaseous phase into the well and thence into the formation. The amine will pierce the sheaths of interstitial water in the formation and be adsorbed on the sand surfaces to render them oleophilic. When the well is then allowed to flow, the pressure of the

50 natural gas will force the displaced water into the borehole and open the channels for the flow of gas. The treatment thus effects an increase in the permeability of the sands to the hydrocarbon phase. Instead of adding the amine treating agent in gaseous form, a hydrocarbon solution of the amine as previously described may also be used in treating natural gas wells if desired.

For the purpose of illustrating the effectiveness of the invention, two comparative runs were made with silica cores, using n-butylamine as the treating agent in one case and isopropylamine in the other. In each run a specially designed flow cell for holding a silica core and flowing through it a hydrocarbon phase and a brine phase simultaneously under standardized constant head conditions was employed. The silica core in each case was made by compressing finely divided silica under a pressure of about 10,000 p.s.i.g. to form a core of about 3/4" I.D. and 2 1/2" length. Permeabilities of the core to both the hydrocarbon and brine phases during and after treatment were determined.

70 In the run made according to the invention, kerosene and brine initially were fed to the core under the con-

stant head conditions; and it was found that the permeabilities of the core to the kerosene and to the brine were 2.5 and 1.0 millidarcies, respectively. The ratio of kerosene to water passing through the core was 1.4 to 1. The core was then treated by continuing the two phase flow but substituting for the plain kerosene a kerosene solution containing 0.10% n-butylamine. It was found that the permeability with respect to the hydrocarbon phase increased to 9.3 millidarcies while that with respect to brine decreased to 0.5 millidarcy. Thereafter the simultaneous flows of kerosene without the amine treating agent and of brine were continued for twenty days, without substantial change in the permeabilities to either phase. The ratio of kerosene to water passing through the core after the treating step was about 30 to 1.

The foregoing results illustrate the effectiveness of the primary amine treating agents herein specified for practicing the invention. By way of comparison a run was made under essentially identical conditions as described above but employing an amine in which the amino group is not attached to a terminal carbon atom, namely, isopropylamine. The core in this case initially had permeabilities to kerosene and to brine of 0.7 and 2.5 millidarcies, respectively. The treatment with isopropylamine had only a small effect on each of these values although the overall effect was adverse. After ten days of treatment the permeability to the hydrocarbon phase had dropped to 0.3 while the permeability to brine had risen slightly to 2.9. This indicates that amines in which the amino group is not attached to a terminal carbon atom are not suitable for practicing the invention.

I claim:

1. Method of facilitating the flow of hydrocarbons

from an underground formation containing hydrocarbons and water which comprises treating the formation with a straight chain aliphatic primary amine selected from the group consisting of methylamine, ethylamine, n-propylamine, n-butylamine and amylamine to render surfaces of the formation oleophilic and increase the hydrocarbon permeability of the formation.

2. Method of treating an oil bearing formation containing water to facilitate the flow of oil which comprises introducing into the formation a hydrocarbon solution containing a minor amount of a straight chain aliphatic primary amine selected from the group consisting of methylamine, ethylamine, n-propylamine, n-butylamine and amylamine.

3. Method according to claim 2 wherein said amine is n-butylamine.

4. Method of treating a natural gas bearing formation containing water to increase the hydrocarbon permeability of the formation which comprises introducing into the formation in gaseous phase a straight chain primary aliphatic amine selected from the group consisting of methylamine, ethylamine, n-propylamine, n-butylamine and amylamine.

5. Mounted according to claim 4 wherein said amine is methylamine.

6. Method according to claim 4 wherein said amine is ethylamine.
